UNITED STATES PATENT OFFICE

RAYMOND A. HENNINGS, OF NEW ORLEANS, LOUISIANA

DESIGN FOR A GAME TABLE

Application filed May 12, 1932. Serial No. 43,772. Term of patent 7 years.

To all whom it may concern:

Be it known that, RAYMOND A. HENNINGS, a citizen of the United States, residing at New Orleans, in the parish of Orleans and State of Louisiana, have invented a new, original, and ornamental Design for Game Table, of which the following is a specification.

Reference being had to the accompanying drawing forming a part thereof,

I claim:

The ornamental design for a game table, as shown.

In testimony whereof I have hereunto set my hand.

RAYMOND A. HENNINGS.
